UNITED STATES PATENT OFFICE.

AUGUST A. BRACY, OF DETROIT, MICHIGAN.

ELECTRICALLY-CONTROLLED PRINT BOX.

Application filed April 30, 1920. Serial No. 377,916.

To all whom it may concern:

Be it known that I, AUGUST A. BRACY, a citizen of the United States, residing at Detroit, in the county of Wayne and State 5 of Michigan, have invented certain new and useful Improvements in Electrically-Controlled Print Boxes, of which the following is a specification.

This invention relates to photographic 10 printing machines, and the primary object of this invention is to provide an improved printing machine, in which the printing light is automatically cut off after a predetermined length of time thereby eliminating 15 the necessity of the printer timing the exposure by means of a watch or the like.

Another object of the invention is to provide an improved printing machine in which the automatic light cut-off can be adjusted 20 so as to cut the light off at any desired time, thus rendering the device applicable for various types of printing paper.

A further object of the invention is to provide an improved printing machine, in 25 which a circuit for the light is closed and the automatic stopping means set in operation when the hinged cover or platen is lowered into engagement with the printing paper, the automatic stopping means opening the circuit after a predetermined length 30 of time.

A further object of the invention is to provide an improved means for closing the circuit and starting the automatic stopping 35 means by an auxiliary lever, when the hinged cover or platen is not being used.

A further object of the invention is to provide a printing machine having an improved type of mask associated with the 40 negative supporting means, which can be adjusted for various sized negatives and which will effectively guard the printing paper from the light.

A further object of the invention is to 45 provide a machine having an improved reflector mounted directly in rear of and below the printing light for directing the rays thereof toward the negative holding means, the reflector being adjustable so as to vary the strength of the light acting on the negative.

A further object of the invention is to provide a printing machine having indicating lights in circuit with the means for closing

and opening the printing light circuit, thereby positively showing to the printer when the printing light is off or on.

A further object of the invention is to provide an improved means for setting the means for opening the lighting circuit, so 60 as to permit the printing light circuit to be opened at any desired time and having means for resetting the printing light circuit closing means, so as to permit the light to act on the negative a slightly longer 65 length of time if the print has not been completed.

A still further object of the invention is to provide an improved printing machine of the above character which is durable and 70 efficient in use, one that is simple and easy to manufacture, and one which may be placed upon the market at a reasonable cost.

Other objects and advantages of the invention will appear in the following detailed description taken in connection with the drawings, forming a part of this specification, in which drawings:

Figure 1 is a vertical longitudinal section through the printing box or machine.

Figure 2 is a front elevation of the box showing the lid in an open position to disclose the interior mechanism of the box.

Figure 3 is a top plan view of the improved printing box or machine.

Figure 4 is a fragmentary vertical longitudinal section through the upper end of the print box looking in the opposite direction from Figure 1.

Figure 5 is a top plan view of the print 90 box showing the platen in a raised position.

Figure 6 is an enlarged fragmentary vertical longitudinal section through the print box showing the means of adjusting the mask.

Figure 7 is a fragmentary side elevation of the print box showing the platen in a lowered position.

Figure 8 is a similar view illustrating the platen in a raised position.

Figure 9 is an enlarged fragmentary horizontal section through the print box illustrating the means for opening and closing the circuits to the magnetic controlling means and the means for returning said circuit opening and closing means to normal position.

Figure 10 is a fragmentary horizontal

section through the forward end of the box showing the sliding plate moved outwardly of the box.

Figure 11 is a fragmentary horizontal section illustrating the reflector for the printing light.

Figure 12 is a diagrammatic view of the circuit for controlling the printing light, signal lights, reading light, and ruby light.

Referring to the drawings, in detail, wherein similar reference characters designate corresponding parts throughout the several views, the letter A indicates the improved printing machine, which includes the casing B; the platen C; the mask D, for the printing paper; the clock mechanism E for controlling the circuit closing and opening mechanism F for the magnet G for controlling the printing light circuit H; the means I for setting the opening contact of the circuit closing and opening mechanism; the means J arranged in the path of the platen for starting and stopping the clock mechanism; the means K operatively connected with the platen for returning the circuit closing and opening mechanism for the magnet G to a normal position; L, the means for returning the circuit closing mechanism to normal position by hand; M, the switch closing device for the lighting circuit, which is operated by the platen; N, the hand operating device for closing the lighting switch mechanism, for returning the circuit closing and opening means to normal position and for operating the clock mechanism, starting and stopping device when the platen is not in use; the reflector O for the printing light, the signals P for indicating when the printing light circuit is opened and closed; and the light Q provided for reading the dials of the setting means of the opening contact of the circuit closing and opening mechanism.

The casing B is of box like configuration and includes the top wall 20, the side walls 21, the rear wall 22, and the front wall 23. The front wall 23 is provided with a door closure 24, which is hingedly connected as at 25 to the front wall 23 of the casing. The door 24 is provided so as to permit the interior mechanism to be viewed by the operator when it is necessary to make repairs or the like thereto. The side walls of the casing adjacent to their lower ends are provided with cleats 26 for the sliding plate 27, which carries the clock mechanism E and the various wires for the light circuit. The plate 27 is arranged so that the same can be slid out of the casing B through the door 24 formed in the casing, so as to permit repairs to be readily made to the electric apparatus and the clock mechanism when necessary. Directly above the plate 27 is arranged a horizontal plate or false bottom 28, which is secured by suitable cleats to the side walls 21

and the rear wall 22. A vertical partition 29 is arranged transversely of the casing B at the central portion thereof and divides the casing B into the printing compartment 30 and the ruby light compartment 31. The vertical transverse partition 29 terminates short of the upper end of the casing B and supports the upwardly and forwardly inclined partition 32 which is held in position by suitable cleats 33. The inclined partition 32 has disposed therein a relatively thick colored glass 34, which permits the light rays emitted from the ruby light 35 arranged in the compartment 31 to shine into the printing light compartment 30. This gives the operator sufficient light to see in the compartment 30 when the printing light 36 is not illuminated. The partition 29 carries the light socket 37 for the ruby light 35 while the plate or false bottom 28 carries the lamp socket 39 for the printing light 36. The printing light 36 may be of any desired candle power which is best suited for the character of the printing being done.

The side walls 21 are provided with openings 40 which are adapted to be closed by ruby colored glasses 41 which are slidably mounted in suitable guide ways 42 secured above and below the openings 40. These colored glasses 41 permit sufficient light to be emitted from the casing so that the operator can see to accomplish his work in a dark room. The upper wall 20 of the casing B is provided with a relatively large opening 43, and the walls of the opening are rabbeted as at 44 for the reception of a relatively heavy glass 45, on which the negatives are adapted to be placed. The light 36 is arranged directly below the glass 45 so that the rays emitted therefrom may shine through the glass 45 onto the negative.

The platen C is provided for holding the printing paper in firm contact with the negative and for preventing the outside light from getting to the printing paper and spoiling the same. The platen C includes a relatively short flat section 46, and a relatively long flat section 47, and the sections 46 and 47 are hingedly connected together as at 48. The rear end of the section 46 of the platen C is hingedly connected as at 49 to the transversely extending bar 50 which is secured to the upper surface of the top wall 20 at the rear edge thereof. The lower surfaces of both sections 46 and 47 of the platen C have secured thereto a felt pad 51, which is adapted to engage the printing paper. The hingedly connected sections 46 and 47 are prevented from collapsing by a sliding bolt 52, which is mounted in a suitable guide 53 secured to the upper surface of the section 47. The forward edge of the section 46 carries a keeper 54 and the bolt 52 is normally held in engagement with the keeper by an expansion spring 55, which is coiled

around the bolt. The outer end of the bolt 52 is provided with an operating handle 56 by means of which the bolt may be withdrawn from engagement with the keeper 54 against the tension of the coil spring 55 so as to permit the section 47 to be swung on the hinges 48. As clearly shown in Figure 1 of the drawings, the coil spring 55 is confined between a collar 57 secured to the bolt 52 and a guide 58. The platen C is held in its lowered position against accidental displacement by a suitable spring pressed bolt 59 carried thereby which is adapted to engage the keeper 60 carried by the upper wall 20 of the casing B. A bracket 61' is arranged at an incline to the vertical axis of the casing and is secured to the upper surface thereof by suitable fastening elements 62' and this bracket 61' is adapted to form a stop 20 for the platen C to prevent the platen from being swung back over the rear end of the casing.

The upper wall 20 of the casing B supports the mask D which includes a pair of relatively thin L-shaped members 61 and 62, which are disposed with their arms directed inwardly toward each other for providing a square frame for engaging the printing paper. The L-shaped members 61 and 30 62 are preferably formed of sheet metal or the like and are adjustably mounted on the upper wall 20 so as to adjust the size of the opening formed by the members. The adjustable means for the members 61 and 62 35 includes a pair of right angularly disposed shafts 63 and 64, and the shafts are supported by suitable bearings 65 at their rear terminals. These bearings 65 are secured to the upper wall of the casing B as clearly 40 shown in Figure 6 of the drawings. The forward ends of the shafts 63 and 64 extend through the front wall 23 and one of the side walls 21 respectively, and the walls are provided with suitable bearings 66 for the reception of the same. The shafts 63 and 45 64 are held against sliding movement in the bearings 65 by means of a head 67 which is carried by the shafts and engages the rear faces of the bearings 65. The forward ends 50 of the shafts 63 and 64 carry wheels 68 having secured thereto the operating handles 69 by means of which the shafts may be readily rotated. The shafts 63 and 64 are screw threaded for a portion of their 55 lengths and carry the travelling nuts 70 the upper terminals of which are provided with inwardly extending recesses 71 for the reception of the pins 72 carried by the L-shaped members 61 and 62. The pins 72 are carried by the lower surface of the L-shaped members intermediate their ends and by rotating the shafts 63 and 64, the members 61 and 62 60 will be drawn towards or away from each other.

Arranged in the casing B and carried by the sliding plate 27 is the clock mechanism E for operating the circuit closing and opening mechanism F for controlling the magnet G, and this clock mechanism E may 70 be of the ordinary or any preferred type, and is secured to the plate 27 by suitable brackets 73. The clock mechanism E is provided with the usual winding stem 74, and a second hand post, to which is secured 75 the upstanding rod 75 for a purpose which will be hereinafter more fully described. One of the wheels of the clock mechanism is extended beyond the casing of the clock and is indicated by the numeral 76 and the means J for starting and stopping the clock mechanism is adapted to engage the said wheel 76 to prevent operation of the clock mechanism F. The circuit closing and 80 opening mechanism for the magnet control G of the light circuit H includes the substantially flat cam shaped plate 77 which is provided adjacent to one end thereof with a circular opening 78, which frictionally receives the cylindrical end of the stem 75 90 secured to the second hand post. This plate 77 is adapted to be moved over the upper surface of the plate 28 into and out of engagement with the contacts 79 and 80, referred to as the opening and closing contacts respectively for the printing light circuit. When the plate 77 engages the circuit closing contact 80 one of the magnets G is energized for closing the circuit to the printing light, and when the plate 77 is 100 moved into engagement with the contact 79 the other magnet is energized for opening the circuit to the printing light. The plate 77 is of an open configuration and the inner walls of the plate 77 is adapted to be engaged by the means K for returning the same to its normal position. The normal position of the plate 77 is in engagement with the contact 80 and when the clock mechanism is started, the same is gradually 105 moved towards the contact 79. The contact 80 is arranged in spaced relation to the contact 79 and merely includes the upstanding angle brackets 81 to which is secured one end of a wire 82 which leads to one of the magnets G. The contact 79 includes the upstanding post 82' which is adjustable toward and away from the plate 77 by the means I, which will be hereinafter more 110 fully described, and this contact is electrically connected by means of a wire 83, to the magnet opposite to the magnet to which the contact 80 is connected. The plate 77 is also connected by a wire 84 which as 115 grounded as at 85 to the clock frame, and this wire is provided for completing the circuit when the plate 77 engages either the contact 79 or 80.

The printing light circuit H includes a pair of spaced conductor wires 86 and 87, 130

which extend from the block 88 carrying the fuse plugs 89. The fuse plugs 89 are electrically connected to the main wires 90 leading from any suitable source of electrical energy. The wire 86 leads to the armature 91 of the electrical magnet controlling means G which will be hereinafter more fully described. The wire 87 leads to one terminal of the printing light 36 and the 10 opposite terminal of the printing light 36 has a wire 92 connected therewith which leads to one terminal 93' of the electric switch 93 which forms part of the means M for closing the electric light circuit H when the platen C is moved into engagement with the printing paper. A wire 94 leads from the opposite terminal 95 of the switch 93 to a contact 96 which is arranged in the path of the armature 91 of the electric magnetic control G, and when the armature contacts with the contact 96, the circuit will be closed and the lamp 36 lit. A wire 97 leads from the contact 93' of the switch 93 to one contact 98 of an electric switch 99 which 20 forms a portion of the hand operating device N for closing the switch mechanism for the light 36 and for returning the circuit opening and closing means of the magnetic control G to its normal position and for 30 operating the clock mechanism starting and stopping device. The opposite terminal 100 of the electric switch 99 has connected thereto a wire 101 which is electrically connected to the contact 95 of the switch 93 and it will be seen that when the contacts of the switch 99 are moved into 35 engagement with each other the circuit H for the printing light 36 will be closed. The plate 27 has secured thereto suitable blocks 40 102, 103 and 104, which carry binding posts for the electric wires of the signal lights P, the reading light Q, and the wires for controlling the energizing of the magnets G. A pair of wires 105 and 106 lead from the 45 binding posts of the fuse block 88 and leads to the terminals of the primary coil 107 of the transformer 108. Wires 109 and 110 are connected to the terminals of the secondary coil 111 of the transformer 108. The 50 wires 109 and 110 lead to binding posts 112 and 113 carried by the block 102, and these posts are connected by wires 114 and 115 to binding posts 116 and 117. The wire 82 leading from the contact 80 is connected 55 to a binding post 118 and a wire 119 extends from this binding post to a binding post 120 carried by the block 104. The binding post 120 is connected to a binding post 121 which has connected thereto a wire 122 which extends to one terminal of the magnet 123 forming the magnetic control G. The opposite terminal of the magnet 123 has connected thereto a wire 124 which 60 leads to a binding post 125 which is electrically connected to a binding post 126 carried by the block 104. A wire 127 is electrically connected to the binding post 126 and extends to the binding post 117 of the block 102 and as stated the binding post 117 is electrically connected to the post 113 70 which is connected by the wire 110 to one terminal of the secondary coil 111. The wire 84 connected to the plate 77 extends to the contact post 116 which is electrically connected to the post 112 which is connected to the wire 109 extending to the opposite terminal of the secondary coil 111. Thus it will be seen that when the plate 77 is moved into engagement with the contact 80 a circuit will be closed through the magnet 123 which will draw the armature 128 carrying the contact 91 into engagement with the contact 96 thus closing the circuit through the printing light 36 when one of the switches 93 and 99 is closed. The wire 85 83 connected with the contact 79 extends to a post 129, which has electrically connected thereto a wire 130 which extends to the binding post 131 of the block 104, which is in turn electrically connected to the binding post 132. The binding post 132 has connected thereto a wire 133 which leads to one terminal of the magnet 134 which is arranged on opposite sides of the armature 128 from the magnet 123. The wire 136 is 95 connected to the opposite terminal of the magnet 134 and is connected to the binding post 125 and when the plate 77 is in contact with the contact 79 the current will flow from the secondary coil 111 100 through the wire 109 through the binding posts 112 and 116 through the wire 84 and the clock frame and the plate 77 to the contact 79 and then through the wire 83 to the binding post 129 through the wire 130 to 105 the wire 133 through the magnet 134, then through the wire 136, through the posts 125 and 126, through the wire 127 and then through the posts 117 and 113 to the wire 110 to the secondary coil. The magnets 110 123 and 134 are secured to a frame 137 and this frame has arranged thereon intermediate the magnets 123 and 134 the upstanding ears 138 which pivotally support the armature 128. The contact 91 carried by the 115 upper end of the armature 128 is in a nature of a set screw so as to permit the adjustment thereof toward or away from the contact 96. The contact 96 includes an angle plate 139 which is secured to the sliding plate 27 120 and this angle plate 139 has its upper horizontal portion extending directly between the magnets 123 and 134 and disposed in the path of the contact 91 carried by the armature 128. The lower end of the angle plate 139 has electrically connected thereto the wire 94. The transformer 108 is provided for reducing the voltage of the current so as to permit the use of the magnets 123 and 134, the signal lights P and the 130 125

reading light Q. The ruby light 35 arranged in the compartment 31 has connected to its terminals the wires 140 and 141, which lead to the block 88 carrying the fuses 89. 5 The reading light Q has connected to its terminal wires 142 and 143, which leads to binding posts 144 and 145, respectively. The binding posts 144 and 145 are connected respectively with the binding posts 146 and 147, which have connected thereto wires 148 and 149, which lead respectively to the binding posts 117 and 116 which are connected through the medium of the wires 114 and 115 binding posts 112 and 113 and wires 109 and 110 to the terminals of the secondary coil 111 of the armature 108. Thus it will be seen that when the switch 150 which is interposed in the wire 142 is closed, the current will flow through the 20 light Q.

The signal lights P includes a green lamp 151, which when lit indicates that the printing lamp is lit, and the red lamp 152 which when lit indicates that the printing light 25 is out. The green light 151 has connected to its terminals wires 153 and 154 which extend respectively to the binding posts 155 which is electrically connected to the binding post 118 and to the binding post 113. 30 Thus it will be seen that the current will flow from the secondary coil to the wire 109 to the binding posts 112 and 116 through the wire 84 through the plate 77, through the contacts 80, through the wire 82, through 35 the posts 118 and 155, through the wire 153, through the lamp 151, then through the wire 154 through the binding post 113 and through the wire 110 back to the secondary coil.

40 The red lamp 152 has connected to its terminal the wires 156 and 157 which lead respectively to the binding posts 113 and the binding posts 158. Thus it will be seen that when the plate 77 is in contact with the contact 79, the current will flow from the secondary coil through the wire 109 through the binding posts 112 and 116, through the wire 84, through the plate 77, contact 79, wire 83, through the contacts 129 and 158 through the wire 157, lamp 152, through the wire 156, through the post 113 and then through the wire 110 through the secondary coil.

45 The means I provided for adjusting the contact 79 toward or away from the plate 77 for energizing the magnet 134 for opening the circuit to the printing light 36 includes the arcuate plate 159, the outer end of which carries the upstanding post 82 forming the contact 79. The arcuate plate or lever 159 is rigidly secured to a vertically extending rod 160, which is rotatably mounted in a suitable bearing 161 riveted or otherwise secured as at 162 to the horizontal plate or false bottom 28. The rod 50

160 extends upwardly through the top wall 20 of the box B and terminates in a head 163 which carries the outwardly extending resilient arm 164, which is adapted to ride over the outer surface of the sector plate 70 165 secured to the upper surface of the top wall 20 of the casing B. The sector plate 165 is provided with a plurality of equidistantly spaced teeth or notches 166, in which the lower surface of the spring arm 75 164 is adapted to engage. Each one of these notches represents a unit of time such as a second, and a suitable dial plate 167 is provided so that the operator may see exactly how many seconds he is setting the 80 exposure for. It can be seen by turning the arm 164 that the post 82 constituting the contact 79 will be moved toward or away from the plate 77 thus permitting the energizing of the magnet 134 at different pre-determined times. The means J provided for stopping and starting the clock mechanism when the platen C is raised or lowered includes a bell crank 168 which is pivotally mounted at its angle to an upstanding bracket 169 which is secured as at 170 to the casing of the clock mechanism E. The lower arm of the bell crank 168 is adapted to be moved into and out of engagement with the balance wheel 76 of the 90 clock, so as to permit the starting and stopping of the clock mechanism when the platen C is lowered. The outer terminal of the upper arm of the bell crank 168 has pivotally connected thereto the upwardly 95 extending link 171, which has its upper terminal secured to the outer end of a lever 172, which is pivotally mounted intermediate its ends upon a depending bracket 173. The bracket 173 is secured to the inner surface of the top wall 20 and extends downwardly therefrom. The inner end of the lever 172 has pivotally connected thereto the upwardly extending rod 174, which slidably extends through the upper wall 20 of 100 the casing and is disposed in the path of the platen C. Thus it will be seen that when the platen C is moved to its lowered position, the lever 172 will be rocked on the bracket 173 and move the lower arm of the 105 bell crank 168 out of engagement with the clock mechanism E and thus start the clock mechanism in operation. This will move the plate 77 over the surface of the clock mechanism toward the contact 79 as here- 110 tofore described.

120 The mechanism K for returning the plate 77 to its normal position, when the platen C is raised for removing the printing paper from the glass 45, includes a crank 175, 125 which is pivotally mounted at its angle upon a pivot pin 176, carried by the inwardly extending bracket 177 which is riveted or otherwise secured as at 178 to one of the side walls 21 of the casing B. The outer arm of 130

the crank 175 carries the depending pin 179, which is adapted to engage the inner surface of the plate 77. When the crank 175 is swung on its pivot 176, the pin will engage the plate and swing the same with the rod 75, carried by the second hand post of the clock mechanism, to contacting position with the contact 80 thus energizing the magnet 123 which will move the armature 128 out of engagement with the contact 96, thus opening the circuit to the printing light and putting the same out. The outer end of the inner arm of the crank 175 has pivotally connected thereto as at 179' the connecting rod 180, which has its outer end, which is connected to the crank 175, curved arcuately as at 181. This rod extends rearwardly through the casing and is slidably supported by the vertical partition 29. The rear end 20 of the rod 180 is pivotally and slidably secured to the lower arm of a vertically disposed bell crank 182, which is pivotally mounted at its angle to a supporting bracket 183, which is riveted or otherwise secured to the rear wall 22 of the casing. The upper arm of the bell crank 182 has pivotally connected thereto, as at 184, the upwardly extending rod 185, which extends through a slot formed in the upper wall 20. The upper end of this rod 185 is pivotally secured to a pivot pin 186, which is carried by the hand operated lever 187. The rear end of the hand operating lever 187 is pivotally connected, as at 188, to the rear end of a plate 189, which is riveted or otherwise secured to the platen C. The plate 189 extends rearwardly of the platen C and is adapted to push the hand operated lever 187 forwardly when the platen C is in its raised position and when the lever is disconnected therefrom. The hand operated lever 187 is adapted to be normally carried by the platen C for movement therewith, by a pivoted catch 190 which is adapted to engage the upper and lower surface of the lever 187. Thus it will be seen that when the lever 187 is connected to the platen C for movement therewith and, when the platen is raised the rod 185 will be moved upwardly rocking the bell crank 182 on the bracket 183, which will push the rod 180 forwardly and swing the crank 175 on its pivot and move the pin 179 into engagement with the plate 77 and return the same to its normal position in engagement with the contact 80.

The mechanism N for returning the plate 77 to its normal position, for operating the clock starting and stopping mechanism I and for operating the switch 99 for closing the circuit to the printing light 36 includes an upwardly extending rod 191, which slidably extends through the upper wall 20, of the casing B. This rod is arranged adjacent to the side edge of the platen C and is adapted to be engaged by an outwardly ex-

tending foot 192 carried by the lever 187 when the lever is disengaged from the platen C and moved forwardly on the upper surface of the casing. The rod 191 is pivoted to a forwardly extending arm 193 which is pivotally mounted at its rear end as at 194 to a depending bracket 195 secured to the lower surface of the top wall 20. The forward end of the arm 193 is provided with an angular extending foot 196, which is disposed directly above the inner end of the lever 172. Thus it will be seen that when the rod 191 is depressed by the lever 187, the lever 172 will be rocked thus moving the bell crank 168 out of engagement with the wheel 76, thus allowing the clock mechanism E to start. The arm 193 has pivotally connected thereto intermediate the foot 196 and the rod 191 a depending link 197 which is pivotally connected to the forward end of the switch lever 198 of the switch 99, which carries spring contact 98 which is adapted to engage the contact 100 carried by the base plate 199 of the switch. The rear end of the switch lever 198 is pivotally mounted as at 200 to a bracket 201 secured to the base plate 199. The contacts 98 and 100 are connected to the wires 97 and 101 as heretofore described. Thus when the arm 193 is operated, the switch 99 will be operated and the circuit closed through the printing light 36. Owing to the fact that the rod 185 is pivotally carried by the lever 187, the plate 77 will be moved to its normal position when the lever is raised. The lever 187 has its outer end provided with a suitable operating handle 202 whereby the lever can be readily raised and lowered by the printer. The operating lever 187 is only used when relatively fast printing paper is used for making the print, at which time the platen C is moved to its rearward position and a flat plate substituted therefor.

The switch 93 is adapted to be operated for closing the circuit to the printing light 36 by the mechanism M, when the platen C is being used and when the platen is moved to its lowered position. The mechanism M includes a rod 204, which is slidably mounted to the upper wall 20 of the casing B and is located opposite to the rods 191 and 174. This rod 204 is arranged on one side of the platen C and is adapted to be engaged and depressed by an outwardly extending foot 205 carried by the platen. The lower end of the rod 204 is pivotally connected as at 206 to the pivoted switch lever 207 of the switch 96. The switch lever 207 carries the contact 93' which is adapted to engage the contact 95 carried by the base 208 of the switch. The contacts 93' and 95 are connected to the wires 94 and 97 as heretofore described. The switch lever 207 is pivotally mounted to a bracket 209 carried by the upper surface of the base plate 208 of the

switch. The switch levers 207 and 198 of the switches 93 and 99 are adapted to be normally held in a raised position by suitable springs, which are coiled around the pivot pins of the levers and engage the levers and the base plates of the switches. Thus it will be seen that the rods 204 and 191 are normally held in a raised position. The lever 172 is normally held in a raised position and the bell crank 168 in engagement with the wheel 76 by means of a contractile coil spring 210 which is secured to the lever adjacent to its inner end and to the inner surface of the wall 20.

15 The reflector O is arranged in the printing compartment 30 directly below the printing light 36 and includes a substantially rectangular frame 210 which carries the mirror 211. The frame 210 is provided with 20 depending ears 212 which receive the transversely extending rod 213. The frame is prevented from movement on the rod 213 by suitable set screws 214, which are carried by the ears and are adapted to engage 25 the rod. The terminals of the rod 213 are rotatably mounted in suitable bearings 214 carried by the side walls 20 of the casing, and one terminal of the rod carries the operating handle 215 whereby the rod may be 30 readily turned for adjusting the mirror in relation to the light 36. The bearings 214 of the rod 213 are made so as to form a relatively snug fit for the rod and thus permit the mirror to be held in adjusted position by frictional contact between the rod and bearings. The signal lights 161 and 35 162 forming the signal mechanism for designating when the circuit through the printing light 36 is opened or closed are arranged adjacent to the spring arm 164 and are carried by the wall 20 of the casing B. The reading light Q is also carried by the upper surface of the top wall 20 and is provided with a suitable reflector 216, which prevents 40 the entrance of light onto the printing paper. This light Q is provided for permitting the printer to see while setting the spring arm 164. The switch 150 provided for the reading light Q is provided with 45 an operating button 217 which slidably extends through the upper wall 20 of the casing and this button is adapted to be depressed to operate the switch when it is desired to close the circuit for the reading light. A depending rod 218 is rotatably carried by the upper wall 20 of the casing and extends therethrough and forms a part 50 of the hand operated means L for returning the plate 77 to its normal position. The lower end of the rod 218 is provided with an offset terminal 219 which is detachably fitted in a socket 220 formed on the plate 77 in rear of the rod 75. The upper end of 55 the rod 218 carries the head 220 by means of which the rod may be readily turned by

the printer for moving the plate 77 to its normal position. The head 220 carries the pointer 221, which is adapted to cooperate with the dial 222, so that the printer may see exactly how far the plate 77 has moved 70 or the exact length of time taken for the plate to move a certain distance.

In operation of the improved printing box, the printer sits or stands at the front end thereof and places a negative on the upper surface of the glass plate 45 and adjusts the members 61 and 62 constituting the mask D by means of the cranks 69 to the size of the negative. The printing paper is then placed in position and the platen C is moved 75 downwardly into engagement therewith and held in its lowered position by means of the spring pressed bolt 59. Prior to the lowering of the platen C the spring arm 164 is moved, so as to adjust the contact 79 in relation to the plate 77 and thereby give the light a predetermined length of time to act upon the negative. When the platen is moved to its lowered position the rod 174 will be depressed, moving the bell crank 158 80 out of the path of the balance wheel 76 and thus start the clock mechanism in operation for moving the plate 77 toward the contact 79. Simultaneous with the depressing of the rod 174, the switch 93 will be closed by 85 means of the rod 204 being depressed by the outwardly extending foot 205, which will light the printing lamp 36. When the plate 77 has been moved by the clock mechanism 90 E to the contact 79, the magnet 134 will be energized as heretofore described, thus moving the contact 91 carried by the armature 178 away from the contact 96 thus putting out the printing light 36. The printer may 95 then draw back the bolt 52 and release the catch 59 and lift the forward section 47 of the platen up to see if the print has been finished. If the print is finished the platen is entirely raised off of the plate 45 and the print removed therefrom and a new piece of 100 printing paper placed on the negative, and the platen then again moved to its lowered position and the process repeated as above 105 described.

If the print is not finished when the 110 printer raises the forward section 47 of the platen, the section may be then lowered and latched in position by the spring pressed bolt 59 and the plate 77 moves back to its normal position in engagement with the contact 80 115 by the rod 218 and the spring arm 164 reset so that the circuit will remain closed for another short space of time. The magnet 134 will again be energized when the plate 77 comes into engagement with the contact 79 120 and the light automatically shut off. The platen may then be lifted and the finished print removed.

If so desired a plate 225 may be provided for engaging the foot 205 and the rod 204 125

for positively holding the switch in engagement with the rod and the rod in its lowered position. The plate 225 is pivotally connected to the upper wall 20 by means of a pivot 5 pin 226 and a thumb piece 227 is formed on the switch to permit the ready operation thereof. One end of the plate may be slightly turned up as at 228 for facilitating the engagement of the catch with the foot 205 or rod 204.

When printing with fast paper, and it is not desired to use the platen, the catch 190 may be operated for disengaging the lever 187 from the platen and the printing paper 15 can then be placed on the upper surface of the negative and the lever 187 moved downwardly which will operate the machine in the same manner as the platen.

From the foregoing description it can be seen that an improved printing box has been provided, in which the circuit for the printing light will be automatically opened and closed by the raising and lowering of the platen.

Changes in details may be made without departing from the spirit or scope of the invention; but,

I claim:

1. In a photographic printing apparatus, 30 a casing having a lamp therein and provided with means for receiving a negative and a sensitized element, an electric circuit for the lamp, a magnetic switch interposed in the circuit, a motor arranged to control the 35 energizing of the magnetic switch, and means operated from the means for receiving the sensitized element for controlling the operation of the motor.

2. In a photographic printing apparatus, 40 a casing having a lamp interposed therein and provided with means for receiving a negative and a sensitized element, an electric circuit for the lamp, a magnetic switch arranged in the circuit for controlling the 45 opening and closing of the same, a motor arranged to control the energizing of the magnetic switch, a platen for holding the sensitized element, and means operated by the platen for starting and stopping the 50 motor.

3. A photographic printing apparatus 55 having a casing provided with a lamp therein, and means for receiving a negative and a sensitized element, an electric circuit for the lamp, a magnetic switch arranged in the circuit for opening and closing the circuit, a clock mechanism arranged to control the energizing of the magnetic switch, a platen for holding the sensitized element, means 60 for controlling the starting and stopping of the clock mechanism, and means of permitting the operation of said control means by the platen or independent of the platen.

4. In a photographic printing apparatus, 65 a casing having a lamp therein and pro-

vided with means for receiving a negative and a sensitized element, an electric circuit for the lamp, a pair of normally opened switches arranged in the circuit, a platen, means operated by the platen for operating 70 one of the switches, and means independent of the platen for operating the other switch.

5. In a photographic printing apparatus, 75 a casing having a lamp therein and provided with means for receiving a negative and a sensitized element, an electric circuit for the lamp, a magnetic switch interposed in the circuit, a clock mechanism for controlling the energizing of the magnetic switch, a second switch interposed in the circuit, a 80 platen for holding the sensitized element, and means operated by the platen for starting and stopping the clock mechanism and for operating the second switch.

6. In a photographic printing apparatus, 85 a casing having a lamp therein and provided with means for receiving a negative and a sensitized element, an electric circuit for the lamp, a magnetic switch interposed in the circuit including a pair of spaced magnets 90 arranged to move the switch to an open or closed position, an electric circuit for the magnets a clock mechanism for controlling the energizing of the magnets, and means for starting and stopping the clock mechanism.

7. In a photographic printing apparatus, 95 a casing having a lamp therein and provided with means for receiving a negative and a sensitized element, an electric circuit for the lamp, a magnetic switch interposed in the circuit, a circuit for the switch a clock mechanism for controlling the energizing of the magnetic switch, means for starting the clock mechanism and means for stopping the clock mechanism at a predetermined time.

8. In a photographic printing apparatus, 100 a casing having a lamp therein and provided with means for receiving a negative and a sensitized element, an electric circuit for the lamp, a magnetic switch interposed in the circuit including a pair of spaced magnets, an armature arranged between the magnets carrying the movable contact of the switch and arranged to engage the stationary contact of the switch, a clock mechanism, 110 a movable electric conducting member connected to the clock mechanism and operated thereby, a normally open electric circuit for each of the magnets including a pair of 115 spaced contacts, each of the circuits of the magnets having one of their contacts disposed on opposite sides of the member, the other contacts of the circuits for the magnets being attached to the member, and means for 120 adjusting one of the spaced contacts of one of the circuits for the magnets toward and away from said member.

9. In a photographic printing apparatus, 125 a casing having a lamp therein and provided 130

with means for receiving a negative and a sensitized element, a normally open electric circuit for the lamp including a movable and a stationary contact, a magnetic switch interposed in the circuit including a pair of spaced magnets, an armature arranged between the magnets carrying the movable contact of the switch, the stationary contacts of the switch being disposed in the path 5 of the movable contact of the switch, an electric circuit for each of the magnets, a switch interposed in each of the circuits for the magnets and each including a spaced stationary contact and a movable contact, 10 the movable contacts of the last mentioned switches being disposed between the stationary contacts of said switches, a clock mechanism operatively connected to the movable contacts of the last mentioned switches for 15 movement away from one of the stationary contacts toward the other contact of the last mentioned switches, and means for starting and stopping the clock mechanism.

10. In a photographic printing apparatus, 25 a casing having a lamp therein and provided with means for receiving a negative and a sensitized element, a normally open electric circuit for the lamp including a stationary and a movable contact, a magnetic switch interposed in the circuit including a pair of spaced magnets, an armature arranged between the magnets carrying the movable contact the stationary contact being disposed in the path of the movable contact, an electric 30 circuit for each of the magnets, an electric switch interposed in each of the circuits for the magnets, one of the switches having a stationary contact, the other switch having a movable contact, a removable plate, 35 the other contacts of the switches being electrically connected to the plate, a clock mechanism arranged to move the plate from the last mentioned stationary contact to the last mentioned adjustable contact, means for 40 starting and stopping the clock mechanism, and means for returning the plate to its normal position.

11. In a photographic printing apparatus, 45 a casing having a lamp therein and provided with means for receiving a negative and a sensitized element, a normally open electric circuit for the lamp including a stationary contact and a movable contact, a magnetic switch interposed in the circuit including 50 a pair of spaced magnets, an armature arranged between the magnets carrying the movable contact the stationary contact being disposed in the path of the movable contact, an electric circuit for each of the magnets, an electric switch for each of the magnet circuits, one of the magnets being arranged to move the armature away from the stationary contact, the other magnet being arranged to move the armature in engagement 55 with the stationary contact, a clock 60

mechanism, a movable plate carried by the clock mechanism, one of the switches in the circuit for one of the magnets having a contact arranged on one side of the plate, the other switch of the circuit for the other magnet having a contact arranged on the opposite side of the plate, the other contacts of the switches for the circuits for the magnets being connected to the plate, an arcuate arm carrying one of the first mentioned contacts of the switches for the magnet circuits arranged on one side of the plate, a rod connected to the arm for adjusting the same, an operating head connected to the rod and arranged on the outer surface of the casing, 70 a sector plate having teeth formed thereon arranged adjacent to the head, and a spring arm carried by the head arranged to engage the sector plate, a platen, and means operated by the platen for starting the clock mechanism and for returning the plate to its 75 normal position after being operated by the clock mechanism.

12. In a photographic printing apparatus, 80 a casing having a lamp therein and provided with means for receiving a negative and a sensitized element, an electric circuit for the lamp, a magnetic switch interposed in the circuit, a circuit for the magnetic switch, a clock mechanism, a plate carried by the clock 85 mechanism arranged to control the energizing of the magnetic switch, means for starting and stopping the clock mechanism, a platen, means operated by the platen for returning the plate to its normal position after 90 being operated by the clock mechanism, and means independent of the platen for returning the plate to its normal position after 95 being operated by the clock mechanism.

13. In a photographic printing apparatus, 100 a casing having a lamp therein provided with means for receiving a negative and a sensitized element, an electric circuit for the lamp, a magnetic switch interposed in the circuit, a second switch interposed in the 105 circuit, an electric circuit for the magnet switch, a platen hingedly carried by the casing, a clock mechanism, a plate operated by the clock mechanism arranged to control the energizing of the magnetic switch, a 110 lever carried by the casing, means for operatively connecting the lever to the platen, and means operated by the lever and platen for starting and stopping the clock mechanism, for closing the second mentioned switch and 115 for returning the plate to its normal position 120 after operation by the clock mechanism.

14. In a photographic printing apparatus, 125 a casing having a lamp therein and provided with means for receiving a negative and a sensitized element, an electric circuit for the lamp, an electric magnetic switch interposed in the circuit, a clock mechanism, a plate operated by the clock mechanism for controlling the energizing of the magnetic 130

- switch, a second switch interposed in the circuit, a platen, means operated by the platen for closing the second switch, a lever pivotally carried by the casing and arranged 5 to close the second mentioned switch and means actuated by said lever for starting and stopping the operation of the clock mechanism and for returning the plate to its normal position.
- 10 15. In a photographic printing apparatus, a casing having a lamp therein and provided with means for receiving a negative and a sensitized element, an electric circuit for the lamp, a magnetic switch interposed in the 15 circuit, a clock mechanism, a control plate carried by the clock mechanism for controlling the energizing of the magnetic switch, an indicator plate arranged on the upper surface of the casing, means carried by the 20 control plate for cooperating with the indicator plate for indicating the movement of the control plate, a second switch arranged in the circuit, a third switch arranged in the circuit, a platen hingedly connected to the 25 upper surface of the casing, means operated by the platen for closing the second mentioned switch, a lever pivotally connected to the casing, means carried by the platen for connecting the lever thereto, means operated by the lever for operating the third 30 mentioned switch, and means operatively connected with the lever for starting and stopping the clock mechanism and for returning the control plate to its normal position.
- 35 16. In a photographic apparatus, a casing having an upper wall provided with means for receiving a negative and a sensitized element, a partition dividing the casing into a pair of compartments and having 40 a vertically disposed lower portion and an inclined upper portion extending beyond one end of the means for receiving the negative and sensitized element, the inclined portion of said portion having a portion formed of translucent material a printing light arranged in one compartment, and an exhibiting light in the other compartment.
- 45 17. In a photographic printing apparatus, 50 a casing having a lamp arranged therein and provided with means for receiving a negative and a sensitized element, an electric circuit for the lamp, a magnetic switch interposed in the circuit, a clock mechanism arranged in the casing, a plate carried by the 55 clock mechanism for controlling the energizing of the magnet, signal lights, circuits for the signal lights, and means operated by the plate for closing and opening the circuit for the signal light.
- 60 18. In a photographic printing apparatus, a mask including a pair of L-shaped members, right angularly disposed rotatable shafts, the shafts being screw threaded for a portion of their lengths, travelling nuts 65 arranged on the threaded portions of the shafts and depending fingers carried by the L-shaped members for detachably engaging the nuts.
- 70 19. In a photographic printing machine, a mask including a pair of independent L-shaped members, a support for the mask, right angularly disposed screw threaded shafts carried by the support, travelling nuts 75 arranged on the shafts, means connecting the L-shaped plates with the nuts, and means for rotating the shafts.
- 80 20. In a photographic printing apparatus, a casing having a lamp therein and provided with means for receiving a negative and a sensitized element, and an adjustable reflector arranged in the casing below said lamp and to one side thereof.
- 85 21. In a photographic printing apparatus, a casing having a lamp therein and provided with means for receiving a negative and a sensitized element, a reflector arranged below and to one side thereof the lamp, and means for adjusting the angle of the reflector in relation to the means for receiving the 90 negative and sensitized element.
- 95 22. In a photographic printing apparatus, a casing having a lamp therein and provided with means for receiving a negative and a sensitized element, a shaft arranged transversely of the casing, means for rotating the shaft, a frame carried by the shaft, and a mirror carried by the frame.

AUGUST A. BRACY.
